UNITED STATES PATENT OFFICE.

JULIUS PHILLIPS, OF TRENTON, NEW JERSEY, ASSIGNOR TO THE LUZERNE RUBBER COMPANY, OF TRENTON, NEW JERSEY, A CORPORATION OF NEW JERSEY.

BALL COCK.

Application filed June 14, 1924. Serial No. 720,087.

To all whom it may concern:

Be it known that I, JULIUS PHILLIPS, a citizen of the United States, residing at Trenton, in the county of Mercer and State 5 of New Jersey, have invented new and useful Improvements in Ball Cocks, of which the following is a specification.

This invention relates to ball cocks and proposes the construction of a float controlled valve particularly adapted for admitting water from a pressure supply to 10 a water-closet flush tank.

The principal object of the invention is 15 the promotion of silence in the filling of the tank.

Another object of the invention is to form the valve and float control of non-metallic, non-corrosive, sound dampening substance.

20 Further objects of the invention will appear as the description proceeds.

In the drawings:—

Figure 1 is a side view of my improved ball cock, the operating means being shown 25 in both open and closed positions.

Figure 2 is a vertical section through the valve casing.

Figure 3 is a view similar to Figure 2 taken at a right angle to Figure 2.

30 Figure 4 is a perspective view of the valve body.

A great deal of thought has been devoted to the endeavor to solve the problem of making silent the filling and discharge 35 operations of flush tanks such as are connected with modern plumbing systems. The illustrative embodiment of the invention disclosed in the present application relates to the filling mechanism, although the

40 broad principles of the invention are equally applicable to the discharge means.

Investigation has shown that the objectionable noise just referred to is caused primarily by the impinging of the supply 45 water under the pressure in the mains against the supply valve and the walls of the valve casing. In the usual metallic construction this noise is communicated to the float through the linkage which connects the valve to the float, and the latter, being a hollow body, acts as a sound box or resonator augmenting the sound and rendering it disagreeably audible.

The present invention arrives at a practical 50 solution of this problem by making

the valve, the valve casing, linkage between the valve and float, and even the float itself, if necessary, of sound-dampening substance such as hard rubber.

Referring now in detail to the several figures, the numeral 1 represents the valve casing formed at its lower end with a threaded nipple or spud 2, the latter being adapted to project through the bottom of the flush tank 3 and to connect with a source of water under pressure. The valve casing is provided with a valve seat 4 communicating by way of the conduit 5 with the source of water supply. A cylindrical valve body 6 is slidably arranged within the valve casing, the lower part of said valve body being formed with a valve head 7 consisting in part of a zone 8 of hard rubber or its equivalent and a terminal portion 9 of soft rubber. The zone 8 and terminal portion 9 are integrally formed, their distinguishing characteristics being produced by differences in the process of vulcanization. The terminal portion 9 constitutes the valve proper and co-acts with the valve seat 4. A plug 10 closes the top of the valve casing. Water discharges from the valve casing, when the valve is open, through passages 11 which are downwardly directed to avoid splashing. An elbow 12 is tapped into the side of the valve casing to which is connected the refill tube 12'. The parts mentioned, and particularly the valve casing and valve body are made of sound dampening substance such as hard rubber, and as it is upon these parts that the entering water impinges, the vibrations ordinarily set up from this cause are, for the most part, inhibited.

Operating means for the valve body consist of a lever 13, preferably S-shaped and fulcrumed between its ends to the valve casing by means of the pin 14, the latter being preferably of hard rubber. The lower end of the lever 13 plays within a slot 15 formed in the valve body, and functions to raise or lower the valve. The float 16 is connected to the lever 13 by means of an arm 17 and said float is angularly adjustable relative to the lever 13 by means of cooperating ratchet faces 18 and 19 formed on the adjacent ends of said lever and arm, which are held together in any position of adjustment by means of the thumb screw 20. The lever 13 and also the arm 17, are

- preferably formed of hard rubber or its equivalent so as to dampen the transmission of such vibrations as are not prevented by the construction of the valve body and valve casing. For structural reasons I have shown the arm 17 as being hollow and provided internally with a metallic stem 21, the latter threading into the float 16. Said stem naturally affects to a slight extent the efficiency of the device in so far as its silent operation is concerned, and may be omitted, if desired, the rubber portion of the arm 17 being in that case threaded for connection to the float.
- 15 While the float itself may be of metal I have preferred to make it, too, of hard rubber, both on account of its non-corrosive property, and for the enhancement of the noiseless operation of the filling mechanism.
- 20 It is to be understood that the invention is not restricted to the detailed construction of the mechanism but contemplates the broad principle of sound inhibition, wherefore I do not restrict myself to the particular construction here disclosed, but only by the terms of the claims and the state of the prior art.
- Having described by invention what I claim as new and desire to secure by Letters Patent, is:—
1. A ball cock for water closet flush tanks comprising a valve, a float for controlling the operation of said valve and an operating connection between said float and valve constituted of rigid members at least one of which is made of sound dampening substance.
  2. A ball cock for water closet flush tanks comprising a valve, a hollow float for controlling the operation of said valve, and an operating connection between said float and valve constituted of rigid members at least one of which is made of sound dampening substance.
  3. A ball cock for water closet flush tanks comprising a valve casing, a valve operable therein for controlling a liquid supply conduit opening within said casing, a hollow
- valve, and rigid connecting members between said float and valve, said valve and valve casing being made of sound dampening substance.
4. A ball cock for water closet flush tanks comprising a valve casing, a liquid supply conduit opening within said casing, a valve operable in the casing for controlling said conduit, said valve comprising hard and soft portions of sound dampening substance, integrally formed, the soft portion co-acting with a seat on the wall of said conduit.
5. A ball cock for water closet flush tanks comprising a valve casing, a liquid supply conduit opening within said casing, a valve operable in the casing for controlling said conduit, said valve comprising hard and soft portions of sound dampening substance, integrally formed, the soft portion co-acting with a seat on the wall of said conduit.
6. A ball cock for water closet flush tanks comprising a valve casing, a valve operable therein for controlling a liquid supply conduit opening within said casing, a hollow float for controlling the operation of said valve, and rigid connecting members between said float and valve, said valve, valve casing, float, and connections being made of sound dampening substance.
7. In a ball cock a hollow hard rubber float and a stem therefor, said stem being made at least in part of hard rubber.
8. In a ball cock a hollow float, a stem therefor, said float and stem being made of non-metallic, sound dampening substance and a metallic reinforcement extending longitudinally within said stem and intersecting the line of juncture between said stem and float.
- In testimony whereof I have hereunto set my hand.

JULIUS PHILLIPS.
